SURFACE FINISH GAUGE

Robert Goodman and Harold D. Rice, Stamford, Conn.

Application August 9, 1954, Serial No. 31,767

Term of patent 14 years

(Cl. D52—1)

The figure is a perspective view of a surface finish gauge embodying our new design. The gauge is of inappreciable thickness.

We claim:

The ornamental design for a surface finish gauge, as shown and described.
